UNITED STATES PATENT OFFICE.

EDWARD H. KIMBALL, OF GLENCOE, ILLINOIS, ASSIGNOR TO JAMES H. SMITH, OF CHICAGO, ILLINOIS.

APPARATUS FOR TRIMMING PHOTOGRAPHIC PRINTS.

SPECIFICATION forming part of Letters Patent No. 673,909, dated May 14, 1901.

Application filed August 15, 1900. Serial No. 26,968. (No model.)

To all whom it may concern.

Be it known that I, EDWARD H. KIMBALL, a citizen of the United States, residing at Glen-
coe, in the county of Cook and State of Illi-
nois, have invented certain new and useful
Improvements in Apparatus for Trimming
Photographic Prints, of which the following
is a specification.

This invention relates to improvements in
apparatus for trimming photographic prints,
and has for one object the provision of an ap-
paratus whereby prints of various sizes may
be properly held and trimmed to the desired
shape.

15 Another object is to have the means for
holding the print while being trimmed ad-
justable in such manner that a wide range of
prints of different sizes and shapes may be
held and trimmed upon the same apparatus
20 without any more skill than is required by
the ordinary trimming apparatus.

A further object is to have the trimming-
plate detachably secured to the means for
holding the print in such manner that said
25 plate will be lifted from the print simultane-
ously with the release thereof without the
necessity for separate handling of the same.

These and such other objects as may here-
inafter appear are attained by the devices
30 illustrated in the accompanying drawings, in
which—

Figure 1 represents a perspective view of
an apparatus embodying my invention in its
simplest form. Fig. 2 represents a trans-
35 verse vertical section thereof. Fig. 3 is a per-
spective view of an apparatus embodying my
invention in its preferred form, and Fig. 4 is
a vertical section thereof on the line 4-4 of
Fig. 3 looking in the direction indicated by
40 the arrows.

Similar letters of reference indicate the
same parts in the several figures of the draw-
ings.

Referring by letter to the accompanying
45 drawings, A indicates a base of any suitable
size and dimensions, and B a bail or guide-
rod rigidly mounted upon the base at one
edge thereof and having slidingly and pivot-
ally attached thereto a pair of spring-arms C,
50 which are, in effect, hinged to the bail so as
to slide longitudinally thereon, said spring-

arms being bent, as clearly shown in Fig. 2,
so as to exert pressure upon the base about
the center of their length, the outer free ends
thereof being bent to form a hook D to en- 55
gage some suitable catch at the opposite edge
of the base.

The base may be composed entirely of metal,
or it may have a metal plate E mounted there-
on, as shown in the drawings, and projecting 60
over one edge of the base, so as to afford a
continuous shoulder for the engagement of
the hooks D at any point along the edge of
the base. Of course the same overhanging
shoulder could be provided on the base if the 65
base were made of a single piece of metal or
any other suitable material. I have shown
in the drawings the plate E as mounted so as
to project above the upper surface of the base;
but obviously it may be countersunk in the 70
base, if desired, or it may be entirely dis-
pensed with and the material of the base
alone relied upon to afford the cutting sur-
face upon which the prints are trimmed.
Pressed upon the plate E by the spring-arm 75
C or upon the upper surface of the base,
where no such plate is used, is a removable
trimming-plate F, having an opening G there-
in of the desired size and shape to which it is
intended to trim the print. This trimming- 80
plate is simply laid upon the base or upon
the plate E, with the photographic print in-
terposed between it and the base or plate E,
and when the spring-arms C are forced down,
so that their hooks engage the shoulder of 85
the base or other suitable catch device pro-
vided therefor, the print will be held firmly
down upon the base and can be trimmed to
the desired shape indicated by the opening
G in the trimming-plate. The trimming- 90
plate is not attached to the base in any man-
ner other than by the pressure of the spring-
arms, and by reason of the ready adjusta-
bility of the spring-arms lengthwise of the
base it will be readily seen that plates of 95
widely-different sizes within the limits of ad-
justment of the spring-arms may be used for
trimming prints in connection with the same
apparatus, the arms being freely adjustable
toward and away from each other and cap- 100
able of being secured at any point in their ad-
justment.

In the preferred embodiment of my invention (shown in Figs. 3 and 4) the spring-arms C are provided with spring-spurs H, between which and said arms the edge of the trimming-plate may be forced, so that when the arms are released from their catches and swung upon the pivoting rod or bail B the trimming-plate will be carried with the arms, and hence the necessity for handling the trimming-plate after the trimming of each print is entirely avoided. Likewise trimming-plates of different sizes and having trimming-openings therein of different sizes and shapes may be readily substituted for one another, the 15 spring spurs or clips H affording a ready means for changing the plates and supporting them in both operative and inoperative position, notwithstanding variations in the size thereof and the shape of the trimming- 20 openings therein.

Such an apparatus is exceedingly cheap, simple, and effective, promotes the efficiency of the operator, and makes comparatively easy the cutting of oval or any other desired 25 shape of print, because the liability of the print to slip under the cutting-plate is obviated and no unusual care need be exercised in handling the apparatus with the print in place.

30 Having thus described my invention, what I claim, and desire to secure by Letters Patent, is—

1. In an apparatus for trimming photographic prints, the combination with a base, 35 and a guide-rod mounted thereon of spring-arms adjustably mounted on said rod, and a catch on the base adapted and arranged to be engaged by the free ends of said arms, substantially as described.

40 2. In an apparatus for trimming photographic prints, the combination with a base and a guide-rod mounted thereon, of spring-arms adjustably mounted on said rod, hooks on the free ends of said arms, and a shoulder 45 on the edge of the base adapted to be engaged by said hooks, substantially as described.

3. In an apparatus for trimming photographic prints, the combination with a base and a guide-rod mounted thereon at one edge

thereof, of a plate mounted on said base and 50 projecting beyond the base at the side opposite said guide-rod, spring-arms adjustably mounted on said rod at one end and hooks on the opposite ends of said arms adapted to engage the projecting edge of the plate, sub- 55 stantially as described.

4. In an apparatus for trimming photographic prints, the combination with a base and a guide-rod mounted thereon at one side thereof, of spring-arms adjustably mounted 60 on said guide-rod, catches on the base adapted to be engaged by the free ends of said arms, and a trimming-plate interposed between said arms and the base, substantially as described.

5. In an apparatus for trimming photographic prints, the combination with a base, a guide-rod mounted thereon at one side thereof, of a plate mounted on said base and projecting beyond the side thereof opposite the guide-rod, spring-arms adjustably mounted 70 at one end on said guide-rod, hooks on said spring-arms adapted to engage the projecting edge of said plate, and a trimming-plate interposed between said spring-arms and the first-mentioned plate, substantially as de- 75 scribed.

6. In an apparatus for trimming photographic prints, the combination with a base and a guide-rod mounted thereon, of spring-arms mounted on said rod, a catch on the 80 base adapted and arranged to be engaged by the free ends of said arms, a trimming-plate and spurs on said arms for receiving the edge of said plate, substantially as described.

7. In an apparatus for trimming photographic prints, the combination with a base and a guide-rod, of spring-arms adjustably mounted on said rod, hooks on the free ends of said arms, a shoulder on the edge of the base adapted to be engaged by said hooks, a 90 trimming-plate and spring-spurs on said arms for receiving the edge of said plate substantially as described.

EDWARD H. KIMBALL.
